STAPLING MACHINE

Roy G. Hoffert, Racine, Wis.

Application July 16, 1937, Serial No. 153,998

1 Claim. (Cl. 1—15)

This invention relates to wire stitching or stapling machines primarily for the stitching or stapling of fibre boxes and the like.

Machines of this type are commonly equipped with a clincher post adapted to enter and support the box to be stapled and to sustain the staple clinching thrust, the post being movable to facilitate entry of the box between it and the staple forming and driving mechanism. In some machines of this type, provision is made for rendering both the movement of the post and the actuation of the stapling mechanism controllable by a single element, ordinarily a pedal lever.

One object of the present invention is to simply and otherwise improve the construction and operation of single-pedal controls for machines of this type.

Another object is to provide an improved single pedal control which may be economically produced, which may be readily adjustable to suit or fit the personal equation of any particular operative and to compensate for wear, and in which those parts subject to wear may be readily replaced.

Another object is to provide improved feed rolls for the wire feed mechanism designed to effect prompt and accurate feeding of the wire to desired lengths, without injury to the wire, and to reduce manufacturing costs to a minimum.

Another object is to provide an actuating cam for the stapling mechanism so constructed as to be capable of production at minimum cost.

Other more specific objects and advantages will appear, expressed or implied, from the following description of an illustrative embodiment of the present invention.

In the accompanying drawings:

Figure 1 is a side elevation, partly in section, of a wire stapling machine constructed in accordance with the present invention.

Fig. 2 is a front elevation of the upper portion of the machine on a larger scale.

Fig. 3 is a sectional view of the wire feed mechanism, taken substantially along the line 3—3 of Fig. 2, on a still larger scale.

Figs. 4 and 5 are views in elevation and section, respectively, of a feed roller, the latter being taken substantially along the line 5—5 of Fig. 4.

Fig. 6 is a fragmentary sectional view of the post operating and control mechanism, shown in elevation in Fig. 1.

Fig. 7 is a sectional view, on a larger scale, of the stapling mechanism cam shown in Fig. 1.

The stapling machine selected for illustration includes a conventional frame comprising a column 10, rising from an appropriate hollow base 11, and having a forwardly projecting goose-neck formation 12 at its upper end.

The forward end of the goose-neck 12 supports a conventional type of stapling head including a reciprocating staple former 13 of well known type actuated by a rotating cam 14 and roller 15, and also including the usual reciprocating staple driver 16 actuated through a link 17 from a wrist pin 18 carried by the cam 14. The cam is fixed to and driven by a shaft 19 which extends horizontally through the goose-neck and which is intermittently actuated through a conventional single-revolution clutch 20 driven through appropriate motor-driven gearing covered by the guard 21. The single-revolution clutch 20 is controlled by the usual pull rod 22, which in this instance extends downwardly through the column 10 to the base 11, and which, when pulled, causes the shaft 19 and 14 to rotate through one complete turn and thereby cause the stapling mechanism to complete a single operating cycle in a well known manner.

The reciprocable driver 16 coacts with a conventional clincher die 23, seated in a head 24, adjustably fixed in the upper end of a post 25 which is supported at its lower end to tilt about a horizontal pivot pin 26 permanently disposed directly beneath the staple driver where it may directly sustain the thrust of the driver.

The wire of which the staples are formed is supplied from a standard reel 21, carried by an upright bracket 28, fixed to the goose-neck 12, and is drawn intermittently therefrom over a conventional tensioning guide 29, by and between a pair of feed rolls 30, and projected through the usual feed tube 31 to the stapling mechanism, where the wire is cut off to proper length, bent to form a staple, and the formed staple driven against the clincher die 23 in a well known manner during each operating cycle.

The post 25 normally assumes the forwardly tilted, full line position of Fig. 1, with its upper end offset forwardly from the stapling mechanism in a position most convenient for the application thereover of a box to be stapled. The post is movable however into the vertical, dotted line position to properly register the clincher die 23 with the staple driver 16, where it may receive and clinch the staple driven through the box material interposed therebetween. In this instance the post 25 is shifted

and controlled by a pedal lever 32 through novel mechanism about to be described, the lever 32 also serving to control the clutch control rod 22 through novel mechanism so combined and 5 arranged as to effect operation of the stapling mechanism only after the post has been shifted into accurate staple clinching position.

In the machine shown, the lower end of the post 25 is rigidly secured to and within a tubular rockable carrier 33 having a pair of spaced depending ears 34 journalled upon the pivot pin 26 which in this instance is in the form of a removable bolt projecting through the ears and through a pair of spaced upright brackets 35 15 preferably removably fixed to the base 11 of the machine by bolts 36 or other appropriate means. The brackets are preferably integrally joined by a cross member 37 (Fig. 6) and are equipped with depending ears 38 between which the pedal lever 32 is rockably supported by a pin 39 passing therethrough.

The post 25 is shifted and controlled by a bell crank 40, rockably supported upon the bolt 23 between the ears 34 of the post carrier 33, and 25 having one arm 41 adjustably connected to the front of the post carrier through appropriate means such as a screw 42. The other depending arm 43 of the bell crank carries a roller 44 mounted upon a pin 45 within the bifurcated end 30 portion 46 of the arm. This roller 44 normally engages beneath a cam lug 47 which projects upwardly and forwardly from the fulcrumed end of the lever 32.

The arrangement is such that when the lever 35 32 is depressed, the lug 47 forces the roller 44 forwardly, thereby tilting the bell crank 40 and shifting the post 25 toward the vertical, dotted line position of Fig. 1. As the lug 47 thus rocks with the lever 32 about the pin 39 it effects a 40 rapid movement of the roller 44 and post 25 until the substantially flat active end of the lug 47 approaches a dead center position between the roller 44 and pin 39 and continued movement of the lug thereafter has no appreciable effect on 45 the position of the post. In this dead center position the post 25 assumes the vertical position shown and the lug acts like a prop to lock the post in that position.

Provision is made for accurately positioning 50 the post 25 in the vertical dotted line position, in order to accurately align the clincher die 23 with the staple driver 16. For this purpose the post carrier 33 is provided with an integral rearwardly projecting stop lug 48 arranged to limit the rearward swing of the post 25 by engaging a stop screw 49 adjustably fixed in the stationary member 37 (Fig. 6), the screw 42 being so adjusted that the post 25 reaches this limiting position as the active end of the lug 47 closely approaches 55 the dead center position above mentioned. It is of course understood that by proper adjustment of the screws 49 and 42 any inaccuracies resulting from manufacture or assembly of the parts, or from wear, may be readily corrected.

The post 25 is preferably normally retained in 60 the full line position of Fig. 1 by appropriate means, such as a tension spring 50, connected at one end to the arm 43 of the bell crank and at the other end to a stationary pin 51 on the base 11. However, when the machine is not in 65 use, and during shipment, the post 25 may be locked in the dotted line position by a yoke 52, rockably supported on pins 53 in the brackets 35, the yoke being arranged to be swung into locking 70 position over the stop lug 48 and to be releasably 75

secured in that position by a screw 54 carried by the yoke and engageable with a notch 55 in the lug 48.

As above pointed out, the pedal lever 32 also serves to actuate the clutch control rod 22 through 5 improved mechanism, which will now be described. The mechanism shown includes a horizontal push rod 56 connected at one end to and actuated by a lug 57 depending from the fulcrumed end of the lever 32. This rod is slidably 10 supported at its other end in an appropriate aperture in the rear end of the base 11. This rod extends loosely through a stationary bracket arm 58 and a lug 59 depending from the fulcrumed end of a lever 60 rockably supported on 15 a horizontal pivot 61 in the base 11.

A compression spring 62, between the bracket 56 and a collar 63, adjustably fixed on the push rod 56, urges the rod toward the pedal lever 32, thereby to yieldably sustain the lever 32 in the 20 elevated position shown (Fig. 1). Another compression spring 64, between the rear end of the base 11 and the lug 59 yieldably sustains the lever 60 in the elevated position shown. The free end of the lever 60 is connected to the lower end of 25 the clutch control rod 22. A collar 65, adjustably fixed to the push rod 56, is arranged to strike the lug 59 and depress the lever 60 and rod 22 when the rod 56 is sufficiently moved by depression of the pedal lever 32. 30

The arrangement is such that initial depression of the pedal lever 32 causes the post 25 to shift into the vertical dotted line staple clinching position of Fig. 1, and thereafter as the active end of the cam lug 47 approaches the above 35 described dead center position between the roller 44 and the lever support 39, the collar 65 strikes the lug 59 and under continued depression of the lever 56 and consequent continued movement of the rod 56, the lever 60 and control rod 22 are 40 depressed by the collar 65, thereby closing the single-revolution clutch 20 and setting the stapling mechanism into operation. It will thus be noted that the stapling mechanism cannot function until the post 25 has first been shifted 45 into vertical clinching position by the initial depression of the pedal lever 32, and that the post is locked in this position by the cam lug 47 until after the pedal lever has again been elevated sufficiently to bring the stapling mechanism to rest by the return of the lever 60 and rod 22 to 50 their original elevated positions.

In the machine shown, the wire feed rollers 30 are driven in synchronism with the stapling mechanism by a gear 66 fixed to the shaft 19 and meshing with one of a pair of intermeshing 55 gears 67 of the same size as the gear 66. The gears 67 are respectively fixed to the rear ends of shafts 68 journalled in appropriate bosses 69 formed on a laterally extended bracket arm 70. The shafts 68, which are thus driven in opposite 60 directions, carry and drive the two feed rollers 30, respectively, fixed to the forward ends thereof.

The feed rollers 30 are of novel design, each 65 comprising a rather heavy sheet metal stamping shaped to provide a disk-like central supporting web 71 and a substantially cylindrical flange 72 having a portion struck up to provide a slightly projecting, concentric, wire feed cam portion 73 70 of predetermined length. In this instance the cam 73 and adjacent portions of the flange 72 of each roller is freed from the web by appropriate means, such as an arcuate slot 74 provided in the periphery of the web, so as to render the 75

freed portions of the flange more or less yieldable and thereby permit the intermediate cam portion, supported thereby, to yield very slightly under the wire gripping pressure. By thus yieldably supporting the cam portion 73 at both ends, a more effective and secure gripping of the wire is obtained and all danger of marring the wire is eliminated. Although in the machine shown, the cam portions of both rollers is thus yieldably supported, excellent results are attainable if only one of the rollers is thus equipped.

Each of the rollers 30 is removably fixed to the end of its supporting shaft 68 by appropriate means, such as a bolt 75, which passes through a central aperture 76 in the web 71 and serves to clamp the web against the end of the shaft. One of the rollers is preferably locked against rotation with respect to its shaft by keys or pins 77 positioned in the shaft and projecting through appropriate notches 78 formed in the periphery of the aperture 76. In order to vary the length of overlap of the opposed cam portions 73 of the rollers, to thereby regulate the length of wire advanced therebetween per cycle of operation, the keys 77 are omitted from the other of the rollers to permit angular adjustment thereof with respect to its shaft.

The cam 14, employed in the machine shown, is of novel construction which permits production thereof at minimum cost. It comprises a two-part structure, including a heavy sheet metal stamping shaped to provide a supporting web 79 having a peripheral flange 80 of desired contour, and a separately formed central member 81, smaller but of similar contour sheared by appropriate dies from a heavy steel plate. The member 81 is permanently fixed to the inner face of the web 79 of the stamping in such posi-

tion that the outer periphery of the member 81, together with the flange 80, form an appropriate cam groove or channel 82 for the roller 15 hereinabove mentioned. Constructed in this manner a cam with an accurately formed groove 5 is provided in which the great expanse heretofore found necessary to mill out and machine such a groove has been eliminated and the cost of materials have also been reduced.

Various changes may be made in the embodiment of the invention hereinabove specifically described without departing from or sacrificing the advantages of the invention as defined in the appended claim.

I claim:

In a stapling machine having a base, a frame carried on the rear of said base, staple-forming and driving mechanism carried on the upper part of said frame, a clincher post pivotally mounted on the front of said base for coaction with said staple forming and driving mechanism, said post being tiltable between work loading and clinching positions, the combination of a treadle lever pivotally mounted in the forward part of said base and projecting through the front 25 thereof, cam means carried by said treadle lever, a member connected to said clincher post and having a roller coating with said cam to tilt said post, a second lever having a fulcrum at the rear of said base and having an arm extending 30 forwardly from said fulcrum, a clutch controlling said staple forming and driving mechanism and connected to said forwardly extending arm, and a rod connecting said treadle lever to said second lever for actuation of said clutch by said 35 treadle lever.

ROY G. HOFFERT.
